FIG. 1.

FIG. 2.

FIG. 4.

FIG. 3.

Inventor

Henry N. Hulander.

UNITED STATES PATENT OFFICE.

HENRY N. HULANDER, OF BROOKLYN, NEW YORK.

SPORT RIDER.

Application filed March 17, 1926. Serial No. 95,442.

This invention relates to gymnastic apparatus and devices and especially to the class wherein a table or suitable board is mounted upon a pair of runners and formed with a narrowed portion which may be straddled by the user and an adjustable rest for the feet.

The main object of the invention is to furnish an apparatus of this class of improved construction in order to enlarge its field of usefulness and to permit various beneficial exercises to be performed by means of its aid.

A further object is to provide a sport rider which may be used by children for play, as well as by adults for gymnastics.

Another object is to have an apparatus of this description which is provided with various appurtenances for every conceivable position of the human body when using the apparatus for exercise, for reading and other purposes.

Other objects and the benefits accruing therefrom will appear hereinafter as this specification proceeds.

In the accompanying drawings:—

Fig. 1 is a perspective view of a sport rider made according to my invention and embodying the same.

Fig. 2 is a plan view of the same apparatus with some of the parts shifted to reveal possible positions thereof.

Fig. 3 is a side view of the apparatus of Fig. 1 in rigid position with the legs down.

Fig. 4 is a view of a portion of Fig. 3 to show the construction and attachment of one pair of legs.

Throughout the views, the same reference numerals indicate the same or duplicate parts.

In the practice of my invention, a pair of runners 22 and 23 are each provided with vertical posts similar to 24, 27, 28 and 29 which are designed to support a table consisting of a main body portion 1 and 2, a narrow portion 3 and a wide end portion 10 and 36.

The main portion of this table has a narrow extension 21 adapted to support the head of a person lying on the whole table, while on the opposite end a movable foot board 13 is located. This board has a pair of end clamps 14 and 15 whereby it is held to the table and is furnished with a foot strap which may confine the toes of a person at 16 when lying forward or face down on the apparatus. For the same purpose a pair of similar cut out

toe holes are provided in the table part 36 at 17 and 18, allowing the user to temporarily dispense with the foot board.

However, the ordinary office of the apparatus may be to form a seat at 2 for a person who desires to use it for rocking exercises, and the legs of the user may straddle the narrow part 3 while allowing the feet to rest on a pair of pedals 8 and 8' provided for this purpose. Naturally, the narrow board 3 may be reinforced for strength with a structure similar to 4 on both sides, while the adjustable pedal or stirrup bar 9 is pivoted at 11 to allow it to swing to various positions, and is furnished with an arced rack or adjustment bar 7. This latter is provided with a series of teeth at 6 which may straddle the bolt 12 on the stationary bar 5 in different positions, mere gravity being depended upon to hold the bar down on the bolt in any given tooth space. The user may either sit up and rock back and forth or may lie down, and thus have the benefit of motion in various ways for improving both circulation and muscular tone.

In order to bring into play diagonal strains and broaden this class of effects, the table has been divided at 19 and 20, allowing the seat 2, narrow portion 3 and shoulder 10 to swivel about a center bolt 38 to various positions in either direction. This is shown in Fig. 2 where it is also seen that the central section rests on a ledge 35 on the far side while being supported about and under the pivot by a shelf 39. Of course, the reinforcement 4 follows part 3 into its various positions, and is therefore furnished with a thumb screw 40 to clamp part 35 between parts 4 and 10, and thus secure the central section in place in any swivelled position. But owing to this divided condition of the table, the reinforcement bar 37 has been inserted between uprights 28 and 29, and, of course, a corresponding bar 37' on the other side of the apparatus.

Sometimes it is desirable to use the apparatus as an operation or rest table, and thus have it rigidly immovable. In order to accomplish this, a pair of legs such as 26 and 49 have been added to the structure, the other extremity having also a pair at 25 in similar fashion. The latter are mounted in a pair of bearing blocks mounted on the runners as at 33, and having an outer block 32 by which to clamp the former to the runner in ques-

tion, while the bolt 34 serves to secure the parts. And on the other hand, the legs 26 and 49 are secured together by a sleeve 41 which is loosely mounted on a bar or rod 46, 5 and the latter is borne at the extremities by a block 45 on runner 23 and bar 37', and by a second block 42 mounted on runner 22 and bar 37. In each case, a block similar to 30 is used to clamp the bearing blocks to the 10 runners and a securing bolt or screw 31 is used to secure the parts in position. On either end of the sleeve 41 is fixed a flange, on one end is plain flange 44, while on the other is a toothed flange 48. A spring 43 on bar 46 15 tends to push the whole toward the block 45 and mesh the toothed flange with teeth 47 on block 45. It is evident that all that is necessary to release the legs in order to raise them or to drop them down to various degrees 20 is that the legs be forced to the left against the spring until the teeth are clear of each other, and when the desired position has been attained, it is but required to permit the spring to force the teeth in mesh again. Of 25 course, both pair of legs are similar in structure, but if an angular position of the table is desired, only one pair of the legs may be used. Or, one pair may be brought down all the way, while the other pair is brought down 30 only part of the way. Also, different angles of table position are attainable by releasing the blocks 30 and 32 by loosening screws 31 and 32 sufficiently to allow the blocks to be slid along the runners to the positions desired, and then again securing the screws. This operation is naturally intended to involve the opposite blocks on runner 23 as 35 well as on 22.

Having now fully described my invention, 40 I claim:—

1. A gymnastic apparatus comprising a pair of runners surmounted by a seat board, and a pair of legs rotatably mounted on said runners and connected by a common sleeve, 45 a block to carry said sleeve mounted on each runner, a bar passing thro' said blocks and said sleeve, a spring mounted against one of said blocks and against said sleeve, a plurality of teeth on the other extremity of said sleeve and corresponding teeth on the other block, and means to secure said blocks to said runners including clamping blocks and securing screws.

2. A gymnastic apparatus comprising a 50 pair of curved runners surmounted by a pair of end boards, a ledge beneath each end board projecting toward each other, a movable board mounted upon said ledges between said end boards, and means to secure said movable board in various positions relative to the end boards.

3. A gymnastic apparatus comprising a 55 pair of runners surmounted by a pair of rigid end boards having each a ledge secured thereto and projecting toward the other, a

movable central board section mounted on said ledges between said end boards and adapted to be flush therewith in all positions, and a pivot in one of said ledges and said movable section with means to secure said 70 section in any attained position.

4. A gymnastic apparatus comprising a pair of curved runners surmounted by a seat board having a relatively narrow section intermediate the extremities thereof, a pendant 75 pedal support movably mounted beneath said narrow section, a pair of pedals on said support, a toothed member pivoted to said support and a cross bar adapted to be engaged by said toothed member in different positions.

5. A gymnastic apparatus comprising a pair of curved runners surmounted by a seat board having a relatively narrow section intermediate the extremities and a foot board 85 movably mounted upon said seat board and provided with end clamps adapted to clamp the edges of said seat board.

6. A gymnastic apparatus comprising a 90 pair of arcuate runners surmounted by a pair of aligned end boards, ledges secured below said end boards projecting toward each other, a pivot on one ledge and a swiveling intermediate section mounted on said ledges and said pivot having a relatively 95 narrow section intermediate the extremities thereof, and means to secure said swiveling section in position.

7. A gymnastic apparatus comprising a 100 pair of runners provided with a seat board secured thereto, a foot support attached beneath said seat board intermediate the extremities of the board, a movable section mounted on said foot support adapted to be extended therefrom or withdrawn to vary 105 the length of said foot support, and foot rests upon said movable section.

8. A gymnastic apparatus including a pair of runners having each a post upon each extremity, a seat upon each pair of adjacent 110 posts providing one seat at each extremity, a relatively narrow board connecting said seats and an intermediate post upon each runner forming an auxiliary support beneath one of said seats.

9. In a gymnastic apparatus, the combination with a pair of curved runners, of a seat surmounting said runners at one of their extremities, a second seat surmounting the 120 runners at their other extremities, there being an intermediate section connecting the two seats, and a pair of posts upon said runners intermediate their extremities arranged beneath one of said seats to form auxiliary supports therefor.

In testimony whereof, I, HENRY N. HÜLANDER, have signed my name to this specification this sixteenth day of March, 1926.

HENRY N. HÜLANDER.
